BY MESNE ASSIGNMENTS, TO RAYMOND CONCRETE PILE COMPANY, OF LOS
ANGELES, CALIFORNIA, A CORPORATION OF NEW JERSEY.

APPARATUS FOR FORMING MOLDS FOR COLUMNS WITH BASES.

Application filed April 26, 1926. Serial No. 104,582.

Our invention relates to the art of forming concrete foundation columns and more particularly to a novel method of an apparatus for forming a mold for a concrete column, 5 the column having a base formed integral therewith at the lower end.

The method in general use at present of making a concrete column in which a base portion of extended diameter is cast integral 10 with the column is as follows:

A vertical hole is dug from the surface of the ground downwardly to the desired depth, this hole being of a diameter equal to that 15 of the base portion of the column which it is desired to form. A wooden form is then constructed in this hole to form a mold for the base portion of the column. A form for the stem of the column is then constructed above the form for the base and communicating with it, the mold for the stem extending upwardly from the mold for the base to the top of the hole. The column is then cast in the mold thus formed. When the 20 concrete is sufficiently hardened the wooden 25 form is removed and the space in the hole about the concrete column is filled in with dirt. This method is expensive to perform inasmuch as the quantity of dirt necessary 30 to be removed in forming a hole of a diameter equal to that of the base portion of the column is many times greater than the volume 35 actually occupied by the concrete column when cast. Moreover, it is expensive to construct the form in the hole after the latter is dug, to remove the form after the column 40 is cast, and to fill in the space about the column with dirt.

It is an object of our present invention, therefore, to produce a method for forming 45 a concrete foundation column which will obviate the necessity for excavating the excessive quantity of dirt which is necessary in the method of present practice described above.

The novel method of our invention, therefore, comprehends the formation of the mold, in which to cast the concrete column, in the soil itself. This method comprises the boring of a hole in the earth, this hole 50 forming the mold for the stem portion of a foundation column. When the hole has

reached a desired depth our method contemplates enlarging the bottom portion of the hole to form a mold for a base portion which will be formed integral with the column when it is cast in the hole. 55

It is therefore the broad object of our invention to provide a method of an apparatus for forming a mold for a concrete column with a base, by boring a vertical hole 60 and enlarging the hole at the lower end to a diameter considerably in excess of that of the hole.

In the development of our apparatus we found it economical and otherwise suitable 65 to devise means for forming a "base mold" in which the power rigging thereof can be used for drilling the hole which forms the mold for the stem of the column. This rigging comprises a standard heavy automobile 70 truck chassis having a rearwardly staggered derrick mounted upon the rear end thereof, a rotary table constructed to be supported upon the derrick and project rearwardly therefrom at a suitable height above the 75 ground, a power transmission whereby the rotary table is rotated by the motor on the chassis, a drill stem whereby a digging bucket may be rotated by the rotary table, and a cable drum operated by the chassis 80 motor for raising the bucket from the bottom of the hole it has dug.

It is another object of our invention therefore to provide an apparatus for forming a mold for a column with a base in which 85 a cutting element is lowered to the bottom of a hole, already bored, and there rotated by a stem operated by a rotary table to cut a base mold cavity of extended diameter from the walls of the hole. 90

It is still another object to provide in an apparatus for forming a mold for a column with a base, a guide member for the cutting element which will cause the latter to be revolved by the drill stem in an orbit concentric with the hole. 95

It is an object of our invention to provide in an apparatus for forming a mold for a column with a base, means whereby the base mold forming cutting element may be held 100 in retracted position within the guide member while it is being lowered into the hole

and whereby the cutting element will be extended in a fixed path while it is being rotated for cutting a base mold at the bottom of the hole.

5 It is desirable to bore the hole and form the base mold while dry. It is therefore necessary to supply means for removing the detritus cut by the cutting element.

Thus another object of our invention is to 10 provide in an apparatus for forming a mold for a column with a base, a bucket which follows the cutting element in its orbit and which automatically collects and retains the detritus removed by the cutting element.

15 It is also an object of our invention to provide in an apparatus for forming a mold for a column with a base, means for retracting a bucket into a guide member and drawing both to a point above the surface of the 20 earth, whereby the dirt may be discharged from said bucket by gravity.

A further object of our invention is to provide in an apparatus for forming a mold for a column with a base, an elevated rotary 25 table which will permit the dirt to be dumped from the bucket while it is beneath the table, thus obviating the necessity for the bucket passing through the rotary table in order for it to attain sufficient altitude 30 to be conveniently dumped.

A still further object of our invention is to provide in an apparatus for forming a mold for a column with a base, a telescopic drill stem which will transmit the rotary movement of the rotary table to the aforesaid 35 guide member and through the latter to the bucket in all positions of the bucket between retracted and extended positions.

Other objects and advantages will be made 40 apparent in the following description and accompanying drawings in which,

Fig. 1 is a diagrammatic vertical sectional view showing a complete apparatus comprising our invention.

45 Fig. 2 is a horizontal section taken on the line 2—2 of Fig. 1.

Fig. 3 is a horizontal section taken on the line 3—3 of Fig. 1.

50 Fig. 4 is a horizontal section taken on the line 4—4 of Fig. 1.

Fig. 5 is a perspective view of the guide member of our invention positioned at the bottom of a hole with the bucket in extended position and showing the undercut base mold 55 as completed.

Fig. 6 is a perspective view of the guide member as it appears when being raised or lowered through the hole and illustrating the bucket in retracted position.

60 Fig. 7 is a perspective view illustrating the guide member suspended from the frame of the rotary table in position for dumping detritus from the bucket which is here shown as re-extended from the guide member.

65 Fig. 8 is a sectional view indicated by the

line 8—8 of Fig. 5, and showing the construction of the hinged floor of the bucket of our invention and the detritus trap which is located adjacent to the cutting element provided on this bucket.

70 Fig. 9 is a bottom plan view of the locking means of the hinged bucket floor.

Fig. 10 is a diagrammatic view illustrating the utility of the extensible telescopic drill stem which is utilized in our invention.

75 Fig. 11 is a detail elevational view of the rotary digging bucket utilized in the apparatus of our invention for digging a stem mold cavity in the earth.

Fig. 12 is a sectional view taken on the line 12—12 of Fig. 11.

Fig. 13 is a perspective view showing the bottom member of the digging bucket of our invention in open position.

Referring to the drawings in detail, it 80 will be seen in Fig. 1 that the mechanism of our invention is carried on a truck chassis 10 which is placed for carrying on its operation in approximately the position shown, relative to a vertical cylindrical hole 11. This 90 hole 11 may have been bored by and desired means previous to the commencing of the base mold forming operation, which is accomplished by means of our invention.

95 Constructed upon the truck chassis 10 is a derrick 12 which is staggered rearwardly as shown and is provided at the peak thereof with a crown block 13. A rotary table frame 15 is built upon the derrick 12 at a considerable height from the ground for a 100 reason which will be explained later. In this frame 15, horizontal members 16 project rearwardly from the derrick 12 and support a rotary table 17. The rotary table 17 comprises an annular shell 20 providing a 105 ball race 21. This race 21 receives balls 22 upon which a ring gear 23 is adapted to rest and rotate. An annular shoulder 24 provided within the ring gear 23 supports a torque frame 25 which is constructed integrally with a splined sleeve 28, so that the latter is disposed concentrically with the ring gear 23. As shown in Fig. 2 the splined sleeve 28 is provided with diametrically 110 opposed internal lugs 29.

115 A pinion 30 meshes with the ring gear 23 and is mounted upon the shaft 31 having bearings 32 and 33 supported upon the horizontal members 16. On the opposite end of the shaft 31 and immediately forward of the bearing 33 is mounted a sprocket 34 having a clutch face 35 formed on the hub thereof. The sprocket 34 rotates freely upon the shaft 31. A clutch member 36 is splined upon the forward end of the shaft 120 31 and is longitudinally movable thereon by means of a bell crank 37 which is mounted upon the frame 15.

125 A counter-shaft 40 is mounted upon the truck chassis 10 in bearings 41 and 42. Up- 130

on the rearmost end of the shaft 40 is keyed 65 a bevel pinion 45 which meshes with a bevel gear 46 which is rotatably mounted upon a shaft 47 which journals in bearings 48, which are mounted upon the truck frame 10. A clutch 50 is operably connected with the bevel gear 46 so that movement of a lever 51 in the direction indicated will connect the bevel gear 46 with a cable drum 52 so that 10 the drum will rotate therewith. The sprocket 55 is mounted upon the shaft 40 so as to register with the sprocket 34 and a link belt 56 connects these two sprockets. A sprocket 60 is rotatable upon the forward 15 end of the shaft 40 and the hub thereof is provided with a clutch face which is adapted to mesh with a clutch member 61 which is splined upon the shaft 40 when the lever 62 is moved in the direction indicated. 20 The truck frame 10 is that of an ordinary truck having front wheels (not shown) and a motor (not shown) situated at the front end of the truck. This motor is provided with a clutch (not shown) from which 25 power is transmitted to a transmission 65 through a drive shaft 66. When the gears in the transmission 65 are properly meshed, power from the motor will be transmitted to the rear wheels 68 through a rear drive 30 shaft 67. A sprocket 70 is secured upon the shaft 66 in registry with the sprocket 60 and is connected to the sprocket 60 by a chain belt 71.

When the apparatus is positioned as 35 shown in Fig. 1 relative to the hole 11, the ring gear 23 is co-axially disposed relative to the cylindrical hole 11.

Suspended within the splined sleeve 28 is the outer tube 75 of a telescoping drill stem 40 76. An annular shoulder 77 formed around the upper end of the tube 76 bears against the upper face of the splined sleeve 28, supporting the tube 75 thereon. Along the outer surface of the tube 75 throughout its 45 length are formed integrally therewith diametrically opposed keys 78 which are adapted to be engaged by the lugs 29, as illustrated in Fig. 2. Within the lower portion of the tube 75 is formed a pair of opposite lugs 80, as shown in Fig. 3. Disposed within the tube 75 is a tube 81 of reduced diameter which is provided throughout its length with diametrically opposed integral keys 82 which are adapted to bear against 50 or be engaged by the lugs 80, as illustrated in Fig. 3. The tube 81 may slide freely down into the tube 75 until an annular shoulder 84 formed around the upper end of the tube 81 engages the upper end of the 55 lugs 80, at which point the tube 81 will be prevented from sliding downwardly relative to the tube 75. Upon the lower end of the tube 81 is formed a horizontal flange 86 which is secured by means of bolts 87 to a

bail 88, the vertical arms of which pass on 65 the inside of and are secured at opposite points to the walls of a cylindrical guide member or shell 90 by rivets 91. The shell 90 has a circular bottom plate 92 and a hole 93 is formed in the wall of the shell 90 directly above the bottom 92, as illustrated clearly in Figs. 1 and 6.

Disposed within the shell 90 are four arcuate tracks 95 which are held in the shell 90 in concentric relation with each other by 75 means of brackets 96, which are rigidly secured to both the tracks 95 and the cylindrical wall of the shell 90. As shown in Fig. 4, the tracks 95 are disposed in embracing relationship about a rectangular space of 80 uniform shape and area. A diaphragm 100 is rigidly secured within the cylindrical shell 90 about the space occupied by the four tracks 95 and is secured to the tracks, acting as a brace. An arcuate digging bucket 103 85 is disposed in the space embraced by the four tracks 95 and is adapted to slide through an arcuate path determined by these tracks. The bucket 103 is rectangular in cross section and is formed of side walls 90 104, inner and outer arcuate walls 105 and 106 respectively, a hinged floor member 107, and a hinged detritus trap 108.

In Fig. 8 the hinged floor member 107 is shown as comprised of a plate having a bottom portion 110 and an end portion 111 bent perpendicularly upwardly from the bottom. Upon the inner edge of the bottom portion 110 are formed tongues 112 which cooperate with similar tongues formed upon the outer wall 106 of the bucket 103 to form the hinge 113. On the inner surface of the end plate 111 is rigidly secured a finger 115, the end portion 116 thereof being provided with a slot 117. In the surface 100 of the inner arcuate wall 105 near the lower edge thereof is formed an indentation 118 which forms a wall 119 disposed substantially parallel with and contacting the finger end 116 when the floor 107 is closed upwardly as shown in Fig. 8.

Means for locking the floor member 107 in closed position as shown in Fig. 8 is provided in a bolt 120, adapted to be disposed through the slot 117, and a suitable hole formed in the wall 119 and having a squared head 121 bearing against the upper surface of the portion 119 and a lug 124 on the lower end thereof adapted to pass through the slot 117 when it is turned to 120 register therewith and to resist passing through the slot 117 when it is turned, as shown in Fig. 9, across said slot 117. Thus when it is desired to unlock the floor member 107 from its closed position as shown in Fig. 8, it is merely necessary to apply a wrench to the head 121 and turn the locking bolt 120 through one-fourth of a revolution,

which will release the floor 107 so that it may fall into the position in which it is shown in Fig. 7.

As shown in Figs. 5, 6 and 8 a cutting element in the form of a shoe 125 is bolted to the outside of the floor member 107. A tongue 126 of the cutting shoe 125 projects upwardly in the curve of the arcuate bucket wall 105, into a cut-way recess 127 thereof.

10 Along the outer edge of this shoe 125 a sharp cutting edge is formed.

The trap 108, as shown in Fig. 8, comprises a metal plate 130 supported by hinges 131 which are secured on the inner surface 15 of the wall 104 adjacent to the cutting shoe 125 so that the plate 130 hangs in a hole 132 formed in this wall 104. These hinges, as will be readily understood, allow the plate 130 to swing inwardly from vertical 20 position but rigidly resist the plate 130 swinging outwardly from vertical.

The bucket 103 has a bail 135, each of the opposite arms of which are pivotally secured by rivets 136 to the side walls 104 of the bucket 103 near the upper edges thereof. A clamp 137 pivotally secures the lower end of a rod 140 to the center of the bail. The rod 140 passes vertically upward through the center of the inner tube 81 and is provided 30 at its upper end with a swivel 142, this swivel connecting at its opposite end 143 with a cable 144. This cable passes vertically upwardly to the crown block 13 over which it passes, returning downwardly 35 therefrom to wind around the cable drum 52.

When in the position shown in Fig. 7, the guide member 90 is supported by hooks 148 which connect the guide member bail 88 to the rotary table torque frame 25. The use 40 of these hooks 148 will be made clear in describing the operation. As also shown in Fig. 7, a belt conveyor 149 is provided having a hinged iron frame 150. A lower drum 151 and an upper drum 152 are mounted upon shafts 153 and 154 respectively, which are suitably journaled in bearings provided upon the frame 150. A continuous conveyor belt 155 passes around the drums 151 45 and 152, as shown. A worm and gear mechanism 157 connects an electric motor 158 with the shaft 154 for operating the drum 152 and effecting the continuous movement of the conveyor belt 155 in the direction of the arrow 159.

In Figs. 10 to 13 is illustrated the rotary digging bucket 198 which may be utilized for the boring of the vertical hole 11. This bucket has a bail 200 which is attached to the flange 86 of the lower end of the inner drill stem tube 81 in the same manner as the bail 88 of the guide shell 90. The lower ends 201 of the arms of the bail 202 are securely attached to a cylindrical digging 60 bucket shell 205, as shown in Fig. 11. The

opposite halves of the bottom edge of the shell 205 are cut as shown in Fig. 13 to provide opposed helical edges 206 and 207. Diametrically opposed vertical edges 208 and 209 connect the adjacent ends of the 70 helical edges 206 and 207.

Hingedly attached by a hinge 201^a to the shell 205 upon the helical edge 206, adjacent to the vertical edge 209, is a digging bucket bottom member 210. This bottom member 75 is clearly illustrated in perspective in Fig. 13. The bottom member 210 has oppositely disposed halves 212 and 213 which are connected together integrally by a central web 214 and vertical peripheral webs 215 and 216. Between the central web 214 and the peripheral webs 215 and 216 are formed 80 openings 217 and 218. The lowermost edge 220 of the opening 217 is formed upon the lowermost radial element of the surface of the bottom member half portion 213, and the lowermost edge 221 of the opening 218 is formed at the lowermost similar element of the bottom member half portion 212. The uppermost edges 223 and 224 of the openings 217 and 218 are formed upon the uppermost similar elements of the bottom member half portions 212 and 213 respectively. The openings 217 and 218 are thus disposed, as shown in Fig. 11, so that upon 95 a right hand rotation of the digging bucket 198 the diametrically opposed openings 217 and 218 will face in the direction of rotation.

The half portions 212 and 213 are helically 100 formed about a center point 227 so that the outer edges 228 and 229 thereof contact with the helical edges 206 and 207 respectively of the digging bucket shell 205 when the bottom member 210 is in its closed position as 105 shown in Fig. 11.

Cutting members 232 have bottom portions 233 slightly inclined inwardly from the horizontal, and vertical peripheral portions 234 formed upon the portions 233 at the outer 110 ends thereof. The members 232 are secured upon the halves 212 and 213 of the bottom member 210 so that each of the cutting members 232 projects a slight distance downwardly from and in advance of one of the 115 edges 220 and 221. Secured upon the bottom member half portion 212 along the edge 223 of the opening 217 is a flap valve 238 which is of such size as to cover the hole 217 and rest in overlapping relationship upon the opposite edge 220 of the hole 217. A flap valve 240 identical with the valve 238 is secured in the same manner along the edge 244 of the hole 218. The manner in which the flap valves 238 are secured to the bottom member 210 and the position in which they rest when closed is best illustrated in Fig. 12.

An elongated hole 242 is formed in the bottom member 210 on the opposite side thereof from the hinge 201^a. A lip 243 is 130

formed upon the horizontal portion of the bail 200 and is apertured to rotatably receive a locking rod 245. The rod 245 has an upper head 246 which rests upon the upper face of the lip 243 when the rod 245 is passed downwardly therethrough. The rod 245 is of such length as to permit the lower end 247 thereof to pass through the elongated opening 242 when the bottom member 210 is in closed position as shown in Fig. 11. An elongated head 249 is integrally formed upon the lower end 247 of the rod 245, the head 249 being of such size as to pass through the hole 242 when it is disposed in longitudinal registry with this hole. When the head 249 is passed downwardly through the hole 242, however, and the rod 245 given a quarter turn, the head 249 is disposed transversely relative to the elongated hole 242 and retains the bottom member 210 in closed position.

In order to dig the stem mold forming cavity 11, the rotary digging bucket 198 is secured to the lower end of the drill stem 81 as shown in Fig. 11, and rotated by the rotary table 17. The digging bucket 198 is then lowered to rest upon the surface of the earth, and as it rotates in this position the cutters 232 bore into the earth. The detritus forced through the openings 217 and 220, disposed above the cutters 232, passes upwardly within the bucket 205 and is retained against returning outwardly through the openings 217 and 218 by the flap valves 238 and 240. When the space 260 within the shell 205 has received a sufficient load of detritus the rotation of the bucket 198 is stopped and the bucket is raised in the same manner as previously described for raising the base mold forming bucket to a position above the mouth 161 of the hole 11. While the bucket 198 is in this position, the conveyor 149 is disposed beneath the bucket 198 and the rod 145 is then given a quarter turn. This brings the head 249 in registry with the elongated opening 242 so that the bottom member 210 swings into the open position in which it is shown in Fig. 13, and the detritus contained in the space 260 in the shell 205 is discharged downwardly by gravity, being carried to a remote dumping place upon the belt 155 of the conveyor 149.

In the operation of our invention, the truck 10 carrying the derrick 12 and the rotary table 17 is positioned as shown in Fig. 1, the hole 11 having been previously drilled down to the bottom surface 160. At this time the tubes 75 and 81 of the telescopic drill stem are telescoped together and are held sufficiently upwardly in the splined sleeve 28 for the cylindrical guide member 90 to be disposed above the upper end 161 of the hole 11, as shown in Fig. 7. The floor member 107 of the bucket 103 is closed and locked in closed position by turning the lug 124 across the opening 117. The motor (not shown) of

the truck 10 is now put in operation, the gears of the transmission 65 remaining in neutral. The shaft 66 revolves with the motor, causing the sprockets 70 and 60 to rotate. The clutch 36 at this time is disengaged. The clutch 61 is now moved into engagement with the sprocket 60 by moving the lever 62 in the direction indicated. This engagement of the clutch 61 causes a rotation of the shaft 40 with the shaft 66 and 75 the consequent rotation with the sprocket 55 of the sprocket 34. Likewise, the bevel gear 46 is rotated in mesh with the bevel pinion 45. The lever 51 is now moved in the direction indicated, causing the cable drum 80 52 to wind up the cable 144 and lift the bucket 103 upwardly until the clamp 137 engages the lower surface of the bail 88. This draws the bucket 103 upwardly into retracted position, as illustrated in Fig. 6, and 85 continued application of tension to the cable 144 through the cable drum 52 raises the telescopic drill stem 76 and the cylindrical guide shell 90 upwardly until the hooks 148 may be removed from the hooking relation 90 as shown in Fig. 7. Upon release of the lever 51, the tension on the cable will be gradually lessened and the cylindrical guide shell 90 with the bucket 103 disposed in retracted position therein, as illustrated in Fig. 95 6, will move gradually downwardly due to gravity through the length of the hole 11 until the bottom plate 92 contacts the bottom 160 of the hole 11. All tension on the cable 144 being released, the weight of the 100 rod 140 is transmitted downwardly through the bail 135 to the bucket 103. As will be seen, at this time the angle formed between the tongue 126 and the end portion of the cutting element 125 contacts the surface of 105 the hole 11 with all the weight of the bucket 103, the bail 135 and the rod 140 tending to force it into the wall.

The clutch 36 is now moved into engagement with the clutch face 35 of the sprocket 110 34 by manipulation of the lever 37, thus causing the rotation of the shaft 31. The pinion 30 being in mesh with the ring gear 23, the latter is thus caused to rotate. Rotating with the ring gear 23, the torque 115 frame 25 transmits its rotation through the lugs 29 to the keys 78 of the outer tube 75 of the telescoping drill stem 76. The rotation of the tube 75 is transmitted through the lugs 80 to the keys 82 of the smaller tube, 120 81, which in turn transmits its rotation to the bail 88 of the cylindrical guide member 90 which commences to rotate in the bottom of the hole. As the guide member 90 rotates, the bucket 103 rotates with it, and the cutting element 125 commences to dig into the surface of the hole. As the rotation of the guide member 90 continues, the cutting element 125 continues to remove dirt from the surface of the hole by virtue of the fact 125 130

that the bucket 103 is constantly fed downwardly by its own weight in the arcuate path of the tracks 95, as best illustrated in Fig. 1. In this figure the bucket 103 is shown partially descended from its retracted position toward its extended position and detritus 180 is shown as having collected inside the bucket 103 due to the action of the cutting blade turning away the dirt from 10 the surface of the hole 11. In this figure a hole 182 is shown as having been turned away and the dotted line 183 indicates the shape of the hole as it will be when the dirt will have been entirely removed. As the 15 dirt is removed by the cutting element 125, it pushes its way into the bucket past the trap 108 and forces dirt already in the bucket 103 upwardly so as to make room for itself in the bottom of the bucket. 20 We have made extensive use of this invention in experimenting to perfect it and have found it convenient to raise the bucket 103 and the guide member 90 from the hole and dump the detritus collected in the 25 bucket 103 several times during the operation of cutting the complete form of a column base as indicated by the dotted line 183 in Fig. 1, and as shown in perspective in Fig. 5. At any time when the operator 30 perceives that a sufficient amount of detritus has collected in the bucket 103 to make it desirable to remove the same therefrom, it is only necessary by manual operation of the lever 37 to disconnect the clutch 36 from the 35 clutch 35, thereby stopping rotation of the guide member 90, and by movement of the lever 51 in the indicated direction to cause a tension to be placed upon the cable 144. This tension transmitted through the bail 40 135 to the bucket 103 will draw the bucket into retracted position, as illustrated in Fig. 6, until the clamp 137 contacts the lower surface of the bail 88. Then and not until then will the upward tension of the cable 45 144 be transmitted to the guide member 90 and start drawing it upwardly from the hole 11. Thus it will be seen that there is no possibility of the bucket 103 obstructing the upward movement of the guide member 50 90 by remaining in the cavity 182. Upon arrival of the bail 88 at a position in close proximity to the torque frame 25, as shown in Fig. 7, the hooks 148 are positioned to connect the bail 88 with the torque frame 25 55 and the tension upon the cable 144 is then released. This will throw the weight of the member 90 and drill stem 75 upon the torque frame 25 and will allow the bucket 103 to slide downwardly through an arcuate 60 path out of the hole 93 into the position substantially in which it is shown in Fig. 5, though instead of being at the bottom of the hole it will be at the top of the hole as shown in Fig. 7. The conveyor 149 is now positioned beneath the guide member 90 and the

wrench is applied to the squared head 121 of the locking bolt 120 and this bolt is turned a quarter of a revolution. This unlocks the hinged floor 107 which opens as shown in Fig. 7. The conveyor being in motion, the detritus as it falls from the bucket 103 is carried on the conveyor belt 155 to a remote place from the hole 11 where it is dumped. Due to the angle of the outer arcuate plate 106 of the bucket 103, the 75 detritus leaves the bucket entirely by gravity. The floor 107 is then re-locked in closed position and the operation as above described is repeated until the cavity 182 is enlarged to the outline indicated by the 80 dotted line 183.

We claim as our invention:

1. In an apparatus for forming a mold for a column with a base, means for removing material surrounding the extreme lower portion of said mold in order to form an enlarged base portion for the mold, said removing means including a cutting device and a receptacle for receiving material direct from said cutting device. 90

2. In an apparatus for forming a mold for a column with a base, means for removing material surrounding the extreme lower portion of said mold in order to form an enlarged base portion for the mold, said removing means including a cutting device, a receptacle for receiving material direct from said cutting device, and means for discharging said material from said receptacle. 95

3. In an apparatus of the class described, the combination of: a guide member adapted to be rotated in a hole; means for lowering said member to the bottom of said hole and raising it therefrom; means for rotating said member at the bottom of said hole; a bucket movably mounted upon said guide member and having retracted and extended positions relative thereto; means for moving said bucket between retracted and extended positions; cutting means provided upon said bucket, said cutting means being adapted to cut away the material surrounding said hole as said bucket moves from retracted position to extended position while said guide member is rotated; and means for capturing the detritus so removed in said bucket. 105

4. In an apparatus of the class described, the combination of: a guide member adapted to be rotated in a hole; a cable for lowering said member to the bottom of said hole and raising it therefrom; a swivel connecting said member and said cable; a telescopic drill stem secured at its lower end to said member and comprising concentrically disposed tubes of successively diminishing diameter, each slidably within the next larger tube and keyed thereto, the aforesaid cable passing through the center of said drill stem; means located outside said hole for rotating said drill stem; a bucket movably mounted upon 110 120 125 130

said guide member and having retracted and extended positions relative thereto, said bucket being attached to the lower end of said cable so as to be drawn into retracted position when said cable is supporting said guide member and to tend of its own weight to move to extended position when said guide member rests upon the bottom of said hole; cutting means provided upon said bucket, said cutting means being adapted to cut away the material surrounding said hole as said bucket moves from retracted position to extended position while said guide member is rotated; and means for capturing 15 the detritus so removed in said bucket.

5. In an apparatus of the class described, the combination of: a guide member adapted to be rotated in a hole; means for lowering said member to the bottom of said hole and 20 raising it therefrom; means for rotating said member at the bottom of said hole; a bucket movably mounted upon said guide member and having retracted and extended positions relative thereto; means for moving 25 said bucket between retracted and extended positions; cutting means provided upon said bucket, said cutting means being adapted to cut away the material surrounding said hole as said bucket moves from retracted position 30 to extended position while said guide member is rotated; means for capturing the detritus so removed in said bucket; and means for discharging the detritus from said bucket when said guide member has been raised 35 out of said hole.

6. In an apparatus of the class described, the combination of: a guide member adapted to be rotated in a hole; a cable for lowering said member to the bottom of said hole and 40 raising it therefrom; a swivel connecting said member and said cable; a telescopic drill stem secured at its lower end to said member and comprising concentrically disposed tubes of successively diminishing diameter, 45 each slidable within the next larger tube and keyed thereto, the aforesaid cable passing through the center of said drill stem; means located outside said hole for rotating said drill stem; a bucket movably mounted 50 upon said guide member and having retracted and extended positions relative thereto, said bucket being attached to the lower end of said cable so as to be drawn into retracted position when said cable is supporting 55 said guide member and to tend of its own weight to move to extended position when said guide member rests upon the bottom of said hole; cutting means provided upon said bucket, said cutting means being 60 adapted to cut away the material surrounding said hole as said bucket moves from retracted position to extended position while said guide member is rotated; and a trap provided in said bucket adjacent to said cutting means, said trap permitting detritus to enter said bucket and retaining it therein. 65

7. In an apparatus of the class described, the combination of: a guide member adapted to be rotated in a hole; means for lowering 70 said member to the bottom of said hole and raising it therefrom; means for rotating said member at the bottom of said hole; a bucket movably mounted upon said guide member and having retracted and extended 75 positions relative thereto; means for moving said bucket between retracted and extended positions; cutting means provided upon said bucket, said cutting means being adapted to cut away the material surrounding said hole 80 as said bucket moves from retracted position to extended position while said guide member is rotated; and a trap provided in said bucket adjacent to said cutting means, said trap permitting detritus to enter said bucket 85 and retaining it therein.

8. In an apparatus of the class described, the combination of: a guide member adapted to be rotated in a hole; a cable for lowering said member to the bottom of said hole and 90 raising it therefrom; a swivel connecting said member and said cable; a telescopic drill stem secured at its lower end to said member and comprising concentrically disposed tubes of successively diminishing diameter, 95 each slidable within the next larger tube and keyed thereto, the aforesaid cable passing through the center of said drill stem; means located outside said hole for rotating said drill stem; a bucket movably mounted 100 upon said guide member and having retracted and extended positions relative thereto, said bucket being attached to the lower end of said cable so as to be drawn into retracted position when said cable is supporting 105 said guide member and to tend of its own weight to move to extended position when said guide member rests upon the bottom of said hole; cutting means provided upon said bucket, said cutting means being 110 adapted to cut away the material surrounding said hole as said bucket moves from retracted position to extended position while said guide member is rotated; and a trap provided in said bucket adjacent to said cutting means, said trap permitting detritus to enter said bucket and retaining it therein. 115

9. In an apparatus of the class described, the combination of: a guide member adapted to be rotated in a hole; means for lowering 120 said member to the bottom of said hole and raising it therefrom; means for rotating said member at the bottom of said hole; a bucket movably mounted upon said guide member and having retracted and extended positions 125 relative thereto; means for moving said bucket between retracted and extended positions; cutting means provided upon said bucket, said cutting means being adapted to cut away the material surrounding said hole 130

as said bucket moves from retracted position to extended position while said guide member is rotated; means for capturing the detritus so removed in said bucket; a hinged floor provided in said bucket having closed and open positions; and locking means holding said floor in closed position during the cutting operation in said hole, and being releasable to allow said floor to move to open position to discharge detritus from said bucket when said guide member has been raised out of said hole.

10. In an apparatus of the class described, the combination of: a guide member adapted to be rotated in a hole; a cable for lowering said member to the bottom of said hole and raising it therefrom; a swivel connecting said member and said cable; a telescopic drill stem secured at its lower end to said member and comprising concentrically disposed tubes of successively diminishing diameter, each slidably within the next larger tube and keyed thereto, the aforesaid cable passing through the center of said drill stem; means 20 located outside said hole for rotating said drill stem; a bucket movably mounted upon said guide member and having retracted and extended positions relative thereto, said bucket being attached to the lower end of said cable so as to be drawn into retracted position when said cable is supporting said guide member and to tend of its own weight to move to extended position when said guide member rests upon the bottom of said hole; 30 cutting means provided upon said bucket, said cutting means being adapted to cut away the material surrounding said hole as said bucket moves from retracted position to extended position while said guide member is rotated; means for capturing the detritus so removed in said bucket; a hinged floor provided in said bucket having closed and open positions; and locking means holding said floor in closed position during the 40 cutting operation in said hole, and being releasable to allow said floor to move to open position to discharge detritus from said bucket when said guide member has been raised out of said hole.

50. 11. In an apparatus of the class described, the combination of: a guide member adapted to be rotated in a hole; means for lowering said member to the bottom of said hole and raising it therefrom; means for 55 rotating said member at the bottom of said hole; a bucket movably mounted upon said guide member and having retracted and extended positions relative thereto; means for moving said bucket between retracted and 60 extended positions; cutting means provided upon said bucket, said cutting means being adapted to cut away the material surrounding said hole as said bucket moves from retracted position to extended position while 65 said guide member is rotated; a trap pro-

vided in said bucket adjacent to said cutting means, said trap permitting detritus to enter said bucket and retaining it therein; a hinged floor provided in said bucket having closed and open positions; and locking 70 means holding said floor in closed position during cutting operation in said hole, and being releaseable to allow said floor to move to open position to discharge detritus from said bucket when said guide member has 75 been raised out of said hole.

12. In an apparatus of the class described, the combination of: a guide member adapted to be rotated in a hole; a cable for lowering said member to the bottom of said hole 80 and raising it therefrom; a swivel connecting said member and said cable; a telescopic drill stem secured at its lower end to said member and comprising concentrically disposed tubes of successively diminishing 85 diameter, each slidably within the next larger tube and keyed thereto, the aforesaid cable passing through the center of said drill stem; means located outside said hole for rotating said drill stem; a bucket movably mounted upon said guide member and having retracted and extended positions relative thereto, said bucket being attached to the lower end of said cable so as to be drawn into retracted position when said 90 cable is supporting said guide member and to tend of its own weight to move to extended position when said guide member rests upon the bottom of said hole; cutting means provided upon said bucket, said cutting means being adapted to cut away the material surrounding said hole as said bucket moves from retracted position to extended position while said guide member is 95 rotated; a trap provided in said bucket adjacent to said cutting means, said trap permitting detritus to enter said bucket and retaining it therein; a hinged floor provided in said bucket having closed and open positions; and locking means holding said floor 100 in closed position during the cutting operation in said hole, and being releasable to allow said floor to move to open position to discharge detritus from said bucket when said guide member has been raised out of 105 said hole.

13. In an apparatus of the class described, the combination of: a guide member adapted to be rotated in a hole; means for lowering said member to the bottom of said hole and raising it therefrom; means for rotating said member at the bottom of said hole; an arcuately formed bucket mounted upon said guide member to move in an arcuate path concentric with the curves of its form 120 and having retracted and extended positions relative to said guide member; means for moving said bucket between retracted and extended positions; cutting means provided upon said bucket, said cutting means being 125

adapted to cut away the material surrounding said hole as said bucket moves from retracted position to extended position while said guide member is rotated; and means for capturing the detritus so removed in said bucket.

14. In an apparatus of the class described, the combination of: a guide member adapted to be rotated in a hole; a cable for lowering 10 said member to the bottom of said hole and raising it therefrom; a swivel connecting said member and said cable; a telescopic drill stem secured at its lower end to said member and comprising concentrically disposed tubes of successively diminishing diameter, each slideable within the next larger tube and keyed thereto, the aforesaid cable passing through the center of said drill stem; a rotary table for rotating said drill 15 stem provided a sufficient distance above the top of said hole to permit the guide member to be suspended therefrom and be entirely removed from the hole for dumping detritus from said bucket; a bucket movably mounted upon said guide member and having retracted and extended positions relative thereto, said bucket being attached to the lower end of said cable so as to be drawn into retracted position when said cable is supporting 20 said guide member and to tend of its own weight to move to extended position when said guide member rests upon the bottom of said hole; cutting means provided upon said bucket, said cutting means being 25 adapted to cut away the material surrounding said hole as said bucket moves from retracted position to extended position while said guide member is rotated; means for capturing the detritus so removed in said 30 bucket; and means for discharging the detritus from said bucket when in dumping position.

15. In a machine of the class described, an under cutting element comprising: a cylindrical shell having a closed bottom, an open top and an opening in said shell just above said bottom; a bail secured to said shell above said open top; a hollow rotary stem secured to said bail for rotating said shell; arcuate tracks provided in said shell; an arcuate bucket slideable in said tracks and adapted to move between a position retracted within said shell and a position extended out through said hole therein; a bail secured on the upper end of said bucket; a cable extending down through said hollow stem and secured at its lower end to said bucket bail; a cutting element provided upon the lower portion of said bucket; and a trap formed in the wall of said bucket adjacent said cutting element for receiving detritus, removed by said element, into said bucket and retaining it therein.

16. In an apparatus for forming a mold

for a column with a base, means for removing material surrounding the extreme lower portion of said mold in order to form an enlarged base portion for the mold, said removing means including a cutting device, a receptacle for receiving material direct from said cutting device, and means for discharging said material from said receptacle outside of said mold.

17. In an apparatus for forming a mold 75 for a column with a base, means for removing material surrounding the extreme lower portion of said mold in order to form an enlarged base portion for the mold, said removing means including a cutting device, a receptacle for receiving material direct from 80 said cutting device, means for withdrawing said receptacle from the mold and means for emptying said receptacle.

18. In an apparatus for forming a mold 85 for a column with a base, a guide member supported by the mold for the column, a cutting device supported by said member, a receptacle coordinated with said cutting device for receiving detritus direct therefrom, 90 and means for actuating said cutting device to radially enlarge a portion of said mold.

19. In an apparatus for forming a mold for a column with a base, a guide member supported by the mold for the column, a cutting device supported by said member, a receptacle coordinated with said cutting device for receiving detritus direct therefrom, 95 means for radially extending said cutting device and receptacle, and means for actuating said cutting device to enlarge a portion 100 of said mold.

20. In an apparatus for forming a mold for a column with a base, a guide member supported by the mold for the column, a cutting device supported by said member, a receptacle coordinated with said cutting device for receiving detritus direct therefrom, 105 means for radially extending said cutting device and receptacle, means for actuating said cutting device while extended, and means for retracting said receptacle while containing material received from said cutting device.

21. In an apparatus for forming a mold for a column with a base, a guide member 115 supported by the mold for the column, a cutting device supported by said member, a receptacle coordinated with said cutting device for receiving detritus direct therefrom, means for radially extending said cutting device and receptacle, means for actuating said cutting device while extended, means for retracting said receptacle while containing material received from said cutting device, 120 and means for discharging the material 125 from said receptacle.

22. In an apparatus for forming a mold for a column with a base, a guide member supported by the mold for the column, a cutting device supported by said member, a 130

receptacle coordinated with said cutting device for receiving detritus direct therefrom, means for radially extending said cutting device and receptacle, means for actuating said cutting device while extended, means for retracting said receptacle while containing material received from said cutting de-

vice, and means for discharging the material from said receptacle outside of said mold.

In testimony whereof, we have hereunto set ¹⁰ our hands at Los Angeles, California, this 19th day of April, 1926.

FRANCIS H. HUNT.

FRANK N. ROPP.
